(57) **CLAIM**

The ornamental design for a tire tread, as shown and described.

DESCRIPTION

FIG. 1 is a perspective view of tire tread in accordance with the present disclosure;

FIG. 2 is a front view thereof;

FIG. 3 is a side view thereof;

FIG. 4 is an enlarged view of a portion of FIG. 2; and, FIG. 5 is an enlarged view of a portion of FIG. 3.

It should be understood that the pattern repeats uniformly throughout the circumference of the tread. Each side of the tire as shown in FIG. 3 is a mirror image of the other side.
